UNITED STATES PATENT OFFICE.

NATHANIEL BALDWIN, OF EAST MILL CREEK, UTAH.

TELEPHONE RECEIVER.

Application filed January 29, 1925. Serial No. 5,516.

The present invention appertains to telephone receivers and embodies a general principle disclosed in my former Patent No. 957,403, issued May 10, 1910, namely, the principle of using an armature actuated by a surrounding coil or coils and acted upon at its ends by four polepieces arranged alternately on opposite sides of the armature as illustrated in Fig. 13 of the above mentioned patent.

The objects of the present invention are to provide a convenient arrangement and magnetic connection of such polepieces, to provide a suitable support for the armature and to provide means to use the armature itself instead of a regular diaphragm for a sound producing element, thus eliminating the armature fulcrum, spring, diaphragm, and connecting link shown in the several figures of the said patent.

I attain these and other objects by the mechanism illustrated in the accompanying drawing in which Fig. 1 is a back view of the instrument with part of the shell and part of the magnet cut away; Fig. 2 is a partial section of the instrument along the line A B of Fig. 1 showing parts in elevation. Fig. 3 is a cross-section of the instrument along the line C D of Fig. 1; Fig. 4 is a back view of a modified form of the structure shown in Fig. 1. Fig. 5 is a longitudinal section of a modified form of armature and Fig. 6 is an elevation of the same.

In the several figures numeral 1 designates the earpiece of the receiver which in the present structure forms a base to which the several parts are secured and held in proper space relations.

The spool 2 is a structure similar to that shown in my former patent but has no fulcrum provided in it. It is inclosed and held in position by the polepieces 3 and 4. These polepieces are formed by bending flat bars of iron into U-shaped pieces with the upper part of one limb and the lower part of the other cut away and fit together over the spool as shown. Projecting edges 5, 5 and 6, 6 formed on the limbs of the polepieces engage the straight edges of the spool 2 and hold it in proper position and the proper spacing between the polepieces is also maintained.

The poles of the magnet 7 are joined to the middle wide portions of the polepieces 3,

and 4 and these parts combined, magnet poles, polepieces, and spool are set into a rectangular recess formed in the earpiece 1. Upstanding lugs 8, 8 at the ends of this recess are provided and screws 9, 9 passing through these lugs, through the magnet 7 and tapped into the polepieces 3 and 4 hold these parts firmly in place.

Transversely to the recess above mentioned a shallow recess 10 is formed in the earpiece 1 over which is placed the armature 11 which armature passes through the spool 2 and between the limbs of the polepieces 3 and 4 without touching either and extends across the said shallow recess 10, over bridges 12, 12 on either side and has its ends fastened under clamps 13, 13 which are adjusted by screws 14, 14. It will be seen that tightening the said screws will tighten the armature which must be tight enough to prevent sticking to the said polepieces. The receiver cord tips 15, 15 are connected to the terminals of the spool winding through the washers 16, 16 to which they are soldered and the cord tips are held in position by the screws 17, 17.

A shell 18 covers the working parts and connects with the earpiece 1.

As shown in Fig. 1 the armature is a straight ribbon of iron or steel. This can be modified by using a thin ribbon 19 of some other material with a magnetic armature 20 attached in the central portion as illustrated in Figs. 5 and 6 or a semi-circular or other shaped diaphragm may be attached or formed integral with the armature at each end as illustrated in Fig. 4.

I claim—

1. A telephone receiver comprising a diaphragm surrounded by an actuating coil; a magnet; four polepiece limbs connected with said magnet and acting upon said armature, two of said limbs being connected with one pole of the magnet and disposed at opposite sides of said coil and on opposite sides of said armature, and the other two polepiece limbs being connected with the other pole of said magnet and disposed in positions opposite to the first two polepiece limbs.

2. A telephone receiver comprising an armature adapted to reproduce sound surrounded by an actuating coil; a magnet; four polepiece limbs connected with said magnet and acting upon said armature, two of said limbs being connected with one pole

of the magnet and disposed at opposite sides of said coil and on opposite sides of said armature, and the other two polepiece limbs being connected with the other pole of said magnet and disposed in positions opposite to the first two polepiece limbs.

3. In combination, an actuating coil, and a vibratile diaphragm extending through said coil transversely to the windings thereof, the said coil being disposed adjacent the medial portion of said diaphragm, the said diaphragm being subjected to magnetic force also.

4. A telephone receiver comprising an armature adapted to reproduce sound, and an actuating coil disposed about said armature intermediate the ends thereof.

5. A telephone receiver comprising a diaphragm supported adjacent two opposite

edges and an actuating coil disposed around 20 that portion of the said diaphragm which is between said supported edges.

6. A telephone receiver comprising an armature adapted to serve the purpose of a diaphragm or sound producing element, a 25 resilient support for said armature and an actuating coil around said armature.

7. A telephone receiver comprising an armature, sound producing extensions on said armature, a resilient support for said armature, and an actuating coil within which 30 said armature extends.

8. A telephone receiver comprising a diaphragm, and an actuating coil disposed about the medial portion thereof, the wind- 35 ings of said coil lying transversely to said diaphragm.

NATHANIEL BALDWIN.
